UNITED STATES PATENT OFFICE

THOMAS OWENS, OF HARRISON, NEW JERSEY, ASSIGNOR TO WILLIAM DIXON, INCORPORATED, OF NEWARK, NEW JERSEY, A CORPORATION OF NEW YORK

COMBINED BRUSH AND BUFFER DEVICE

Application filed July 15, 1931. Serial No. 550,850.

This invention relates to improvements in a combined brush and buffer construction. More particularly it relates to compactly made combined brushing and buffering device.

5 It is an object of this invention to provide a combined brush and buffer to avoid the necessity of using separate equipment for maintaining and using brushes and polishing or buffering wheels.

10 Still another object is to provide a compactly and simply designed combined brush and buffer for use in cleaning and polishing the surface of various objects.

15 A further object of this invention is to provide an efficient polishing and buffering implement having buffering means in spaced apart relation with respect to the brushing means thereon.

20 With the above objects and features in view, the invention in its preferred embodiment includes a combined brush and buffer with the respective brushing and buffering members in spaced apart relation along the periphery or surface of a hub or base and means for retaining the respective members 25 in position therein in series.

The invention in its preferred embodiment consists in the details of construction and the arrangement of the several parts which 30 will be more fully described and claimed.

Referring in detail to the drawings wherein is shown one simple and practical embodiment of the invention, and in which similar reference characters designate corresponding 35 parts throughout the several views,—

Figure 1 is a side view partly cut away, of the subject matter of the present invention in its preferred embodiment;

Fig. 2 is a view on line 2—2 of Fig. 1;

40 Fig. 3 is a perspective view of a bundle of bristles containing a string, ready for assembly in accordance with the present invention; and

Fig. 4 is a view on line 4—4 of Fig. 2, showing the bundle of bristles containing a string

in assembled position for holding the buffering material in fixed relation to the bundle.

In the drawings which, for the sake of illustration and clarity, show the preferred embodiment of the invention; a hub 10 made 50 of any desirable material, but preferably of wood and having a central or axial bore 12, passing through the hub along its longitudinal axis and adapted for engagement by a driving shaft, not shown, has a plurality of 55 holes or bores 14 radially extending inwardly from the periphery of the hub toward the central bore 12 of the wheel.

The holes 14 of the hub are arranged in series on the periphery of the hub and each 60 series is in spaced relation along the length of the hub. In order to afford a more continuous brushing line when the completed device is in use, the holes 14 in each series are in staggered relation with the next series of 65 holes so that the holes of alternate rows would be in alignment with each other. The holes 14 may be of any diameter depending upon the amount of bristle material to be embedded and retained therein. Adapted for insertion within the holes 14 are fascicles or bundles of bristles 16 containing a string or connecting means 18 and which are retained in firmly engaged position within the holes by means of a staple 20. One end of string 18 70 is in fixed connection with a pad of buffering material 22 to be hereinafter more fully described. The bundle of bristles are of substantially equal length and are sufficiently large so that when it is to be folded in two 75 parts to be inserted in the holes 14 only little free space would remain therein between the bristles and the wall of each hole. When the bristle bundles 16 are set in the holes corresponding with the series of holes in the hub 80 10, and one series is made, a compacted pad of concentrically shaped buffering material 22 is attached against such series of bundles.

The buffering material used may be of any suitable kind, such as chamois, cotton, felt, 85

- or other soft material which is commonly used in the buffing art. The inner circumference of the pad 22 is in contact with the periphery of the hub 10. The edges of the pad 22 adjacent their inner circumference may be sewed to keep the individual sheets 24 of the buffing material constituting the pad in compact form so that when the device is used the sheets will not tend to slip and slide over each other due to the rotary motion imparted thereto during its use on a machine.

- In order to keep the buffing material pad 22 in stationary position with respect to the periphery of the hub, strings or connecting means 18 are passed through the pad of material at a point preferably near the marginal edge of the inner circumference. The end of the string 18 holding the pad in relative stationary position may be knotted or sewed into the pad as long as an effective holding engagement with the pad is obtained. Furthermore, the strings 18 may be disposed at spaced intervals along the inner circumference of the pad 22 to afford a multiple engagement with the bristle bundles 16 and keep the parts in relative stationary position.

The outer circumference of the sheets of buffing material pad 22 is left free so as to provide as much of the material for buffing or polishing. As an object is being buffed and brushed by a device embodied in the present invention, the buffing material intermediate the bristles covers a large surface area of the object. By this arrangement of the pads 22 interposed between series of bristle bundles, a combined and effective action of brushing and buffing is effected on an object to be polished.

- By way of illustrating one method of attaching a bundle of bristles containing connecting means thereon for the buffing material to the sides of the holes of hub 10, a plurality of bristles are brought together with a string 18 to form a fascicle or bundle, as shown in Fig. 3. A staple 20 is placed around the middle of the bundle of bristles and driven into holes 14 arranged on the hub 10. As the sharp ends of the staple 20 are driven into the hub and around the opening 14, the bundle of bristles with the free end of string 18 contained therein is folded into two parts whereby they become intimately mixed to form a compact mass at the part protruding from the hole 14, while the bristles at the upper part of the bundle are spread out. As the free end of string 18 becomes enmeshed in the folded bundle of bristles in the hub, the end attached to the buffing pad is drawn so as to pull the pad against the hub 10. The ends of the bristles and the buffing pad may then be trimmed to afford an even polishing and brushing edge.

From the foregoing description of the preferred embodiment of the present invention, it will be noted that a combined brush and

buffing wheel is obtained, in which the bristle fascicles or bundles retain, as enclosing means, a cord or string in engagement or connection with a pad of concentrically shaped buffing material having the same general outline as the brush bristles, while the buffing pads are interposed between successive rows of bristles and have the outer circumference free to spread out and afford a maximum of polishing surface. It is to be understood that the pads may be secured to the hub of the device in any manner.

Although the description includes the use of a cord or string to be used in connection with the buffing pad and the bristle bundles, such connecting cord may be eliminated and a pad of buffing material may be used which will have an inner circumference slightly smaller than that of the hub of the wheel so as to form a close fit against the hub.

In the use of a combined brushing and buffing device, as herein described, there is a saving in time and in equipment and material required over that now used in the brushing and polishing of plated materials.

While one embodiment of the invention in its preferred form has been hereinabove described and shown, it is to be understood that various modifications and changes as to form, arrangement, construction, and size may be made without departing from the spirit and scope of the invention. Accordingly, the privilege is hereby reserved of making any and all changes without being limited in the spirit and scope of the invention as defined in the following appended claims.

I claim:—

1. A combined brush and buffer consisting of a plurality of spaced rows of bristle bundles disposed in the hub, pads of buffing material intermediate the rows of said bristle bundles and surrounding the periphery of the hub, a cord connected with the pads and extending into a bristle bundle in the hub thereof, and a staple for retaining said bristle bundles and also the cord tautly whereby the latter draws the inner edge of the pads against the hub to prevent slipping of the same around the hub.

2. In a combined brushing and buffing device having a rotary hub with series of holes arranged at spaced intervals along its periphery, and bristle bundles inserted within each of said holes, the improvement consisting of pads of buffing material interposed between successive rows of bristle bundles, and a cord attached to the pad and retained within a bristle bundle for retaining said pads in relatively stationary position on the hub.

3. In a brushing and buffing device having a rotary hub with holes arranged around it in spaced planes perpendicular to its axis and bristle bundles inserted within the holes,

the improvement consisting of ring-shaped sheets of buffing material interposed between successive rows of bristle bundles, anchoring means with one end fixed to the inner edge 5 of said pads of buffing material adjacent the hub and the other end in connection with a bristle bundle in one of the holes in the hub, and means within the holes of the hub for retaining said bundles and the connected 10 end of the anchoring means within the side walls surrounding the opening in the hub.

In testimony that I claim the foregoing as my invention, I have signed my name hereto.
